UNITED STATES PATENT OFFICE.

VALDEMAR F. LÄSSOE, OF BROOKLYN, NEW YORK.

OIL-BURNER.

957,614.

Specification of Letters Patent. Patented May 10, 1910.

Application filed December 16, 1908. Serial No. 467,741.

To all whom it may concern:

Be it known that I, VALDEMAR F. LÄSSOE, a citizen of the United States, and a resident of the borough of Brooklyn, in the county of Kings and State of New York, have invented certain new and useful Improvements in Oil-Burners, of which the following is a specification.

This invention relates to oil burners, and its organization comprises means for spraying fuel, oil and the like into a mixing chamber and sub-dividing it in said chamber by a multiple series of transversely-acting currents of a spraying medium such as steam, or air under pressure. The said currents enhance the division of the oil into a fine spray, and establish the intimate mixing of the oil and spraying medium before the mixture is delivered from the burner.

The invention is characterized by means for at all times maintaining operative, the appurtenances that control the quantities of the fuel and the spraying medium which are to be mixed, irrespective of the effects of expansion and contraction to which the burner is subjected, by virtue of changes of temperature.

The objects of the invention are secured by locating the operative means for changing the discharge capacities of the fuel and the spraying medium outlets in close proximity to said outlets, so that changes of temperature will not interfere with the adjustments of said outlets and their efficient operation. The said operative means are further characterized by having parts connected thereto that do not come in the path of any stops and the like, which would hinder their operation when subjected to changes of length and form by changes of temperature, due to the spraying medium or the furnace for which the burner is provided.

The burner is further characterized by a fuel or oil strainer which is directly connected to the burner, and by the disconnection of which means are obtained for its easy cleaning, as well as for the cleaning of the burner.

Referring to the drawings, Figure 1 shows a top plan view of a burner exemplifying the invention, Fig. 2 represents a partial vertical section of Fig. 1 on the line 2, 2, Fig. 3 represents a fragmentary portion of the right hand end of Fig. 2 with some of

the parts shown in full, Fig. 4 is a side elevation of Fig. 1, Figs. 5, 6, 7 and 8 show sections of Fig. 2 respectively on the lines 5-5, 6-6, 7-7 and 8-8, Fig. 9 represents an end view of the spraying cap, Fig. 10 shows a left hand view of Fig. 4, Fig. 11 is an enlarged view of the right hand portion of Fig. 2, Fig. 12 represents the burner connected with a boiler with natural draft, Fig. 13 is a left hand front view of Fig. 12, Fig. 14 represents the burner with a boiler having forced draft appurtenances, Fig. 15 shows a front elevation of a water tube boiler with a number of the burners connected thereto and Fig. 16 represents a partial section of Fig. 15 on the line 16, 16.

The burner is shown with a body comprising respectively the outer and inner cylindrical steam or air tubes 30 and 31. The tube 30 is supported by a bushing 32 having the flange 33 with the openings for the bolts 34. A dial plate 35 with the scale 36 and elongated openings 37 is located adjacent to the outer face of the flange 33. The inner face of said flange bears against the front 38 of a furnace with which the burner is connected, and the bolts 34 clamp the dial 35, the flange 33 and the front 38 of the furnace together. A pointer 45 for the scale 36 is fastened to the outer tube 30 and carries the operating handle 46. On the inner surface of the tube 30 are formed the circular projecting lugs 47, and the projecting ring 48 that constitute guides for the inner tube 31. The ring 48 also constitutes the bottom of a stuffing box between the said outer and inner tubes of the burner. A gland 49 bears against the packing 50, and a screw cap 51 is provided for said stuffing box. A drain cock 57 is connected with the tube 30.

The outer end of the tube 30 is threaded at 52 to support the spraying head to be described, and adjacent to said threads is formed an inner collar 53 having openings 54, and the large threads 55 of very coarse pitch that support the threads 56 formed on the outer surface of the oil barrel 58. The barrel 53 at its rear end is threaded at 73 for the oil pipe or conduit 59, and at its front end is threaded for the oil nozzle 60. The nozzle 60 is fluted on its outer cylindrical surface as shown at 61, and has formed therewith the needle valve seat 62 and port 63, and flat end face 64.

The spraying head comprises the ring 110.

bushing 65 and the cap 66. The bushing 65 has an outer threaded cylindrical surface that engages the threads 52 and inner threads 67 which are in engagement with the cap 66. 5 A ring flange 68 extends inwardly toward the central opening 69 of the said bushing 65. The cap 66 has an inner central cavity 70, an outer cavity 71, and tapering outlets 72 extend radially outward through the said 10 cap from the inner cavity 70.

The oil barrel 58 has formed in about its inner central portion the threaded boss 80 and the conduits 81.

The oil pipe 59 has formed on one end a 15 thread 82 which is in engagement with a corresponding thread of the oil chamber 83. A collar 84 on the pipe 59 bears against the edge of said oil chamber, and a collar 85 at the other end of the said pipe bears against 20 the oil barrel 58. The chamber 83 has a threaded nozzle 86 which is in engagement with the rear end of the inner tube 31. The latter tube has the inlet barrels 87 to which are connected piping 88 with the unions 89 25 and the valves 90 and 91, for the introduction of either steam or air under various pressures.

The oil chamber 83 has formed at its rear 30 end a neck 95, which is threaded on its outer cylindrical surface for a cap 96, and the latter forms therewith a stuffing box having the packing 97. From the lower portion of the oil chamber 83 extends the oil strainer chamber 100 which is threaded at the lower 35 portion thereof for the foot 101 of an oil strainer, a washer 102 being interposed between the edge of the chamber 100 and the foot 101.

A barrel 103 with perforations 104 extends up from the foot 101. Inlet barrels 105, 106 are formed with the chamber 100, in the former of which is shown a plug 107 and in the latter the piping 108 with the union 109, and valve 110, for the introduction 40 of the oil to be used in the burner.

A valve rod 114 with hand wheel 115 is supported at one end in the neck 95 and passes through the oil chamber 83 and oil pipe 59. It has formed therewith a threaded portion 116 which is in engagement with the threaded boss 80 of the oil barrel 58, and beyond the portion 116 extends the 50 needle valve 117 that can engage the needle valve seat 62 of the nozzle 60.

To operate the invention and referring to Figs. 1 to 11, after the burner has been placed in position within a furnace the operator opens either one of the valves 90 or 91, the operating handle 46 having been moved 55 to axially move the tube 30, to allow an opening between the ring flange 68 and the outer face of the oil nozzle 60 to admit steam or air under pressure.

Supposing the burner is used with steam, 60 the latter finds its way into the annular

channel 120, between the inner tube 31 and oil pipe 59, from whence it flows through the openings 54 of the collar 53 at the outer end of the tube 30, then through the disk-like cavity between the end face of oil barrel 58 70 and the inner face of the bushing 65, and then the steam flows through the depressions of the fluted cylindrical surface 61 of the oil nozzle 60. The steam now strikes the ring flange 68 which diverts it in directions perpendicular to its flow, and then it enters the inner central cavity 70 of the cap 66, in which it is mixed with the oil to be described. 75

While the steam is passing through the 80 burner, oil is forced through the piping 108 with its valve 110 and enters the chamber 100, from which latter it is forced through the perforations 104 of the barrel 103 of the strainer. The oil then finds its 85 way into the oil chamber 83, through the oil pipe 59, then through the conduits 81 into the oil nozzle, and passing the needle valve 117 flows through the port 63, into the cavity 70, in which latter it mixes with 90 the steam in the form of spray and the mixture is discharged through the tapering outlets 72 in the cap 66 of the spraying head.

The location of the needle valve 117 with respect to its seat in the oil nozzle is controlled by the hand wheel 115. The amount of steam admitted is regulated by the distance between the end face of the oil nozzle 60 and the inner face of the collar 68 of the ring bushing 65, which latter is regulated by 95 the location of the pointer 45 on the scale 33. When the handle 46 is moved it carries with it the outer tube 30, and the threads 55 thereof coacting with the threads 56 of the oil barrel 58 separate the tube 30 with the bushing 65 and the oil nozzle 60. 100

It will be noted that the flat end face 64 of the oil nozzle 60 constitutes a steam valve, which coacts with the accompanying face of the ring flange 68 of the bushing 65. 110

In Figs. 12 and 13 a boiler is represented for natural draft, having the corrugated furnace 121 with the circular brick arch 122, and the annular space 123 between the furnace and said arch. The front 124 has connected therewith the damper 125, and the burner with the outer tube 30 and pointer 45 is connected to said front 124. 115

In Fig. 14 a boiler is shown with a furnace 130, to the front of which are connected appurtenances with a slide 131, through which heated air is forced into the furnace. The oil burner with the outer tube 30 is connected to the front plate 132 of the furnace, and the latter has the brick arch 133 with 125 the annular space 134 around the same.

In Figs. 15 and 16, is shown a water tube boiler with the front 135, to which are connected a number of the burners having the outer tubes 30 and pointers 45 by means of 130

the steam piping 136 and the oil piping 137. Circular brick arches 138 are located in the furnace, in front of each burner to maintain the oil at a high temperature, in proximity to the burner. The circular arches shown with the boilers are maintained at a high temperature and are useful to relight the burners in case they become extinguished, by simply allowing the mixture from the burner to strike the said arches.

Having described my invention, I claim:

1. The combination in a burner of an outer tube, a spraying head connected with said tube, a valve seat formed in said head, an oil barrel located in the outer tube and in threaded engagement therewith, a threaded boss in the oil barrel, an oil nozzle extending from the oil barrel having a valve seat formed therein and its outer end face coacting with the valve seat in the spraying head, a valve in engagement with the threaded boss of the oil barrel and coacting with the valve seat in the nozzle, means to rotate the said tube and thereby axially move the spraying head having the valve seat, and means to turn and thereby axially move the second valve.

2. The combination in an oil burner of an outer tube for the body, an inner tube slidably connected with the outer tube, and having an inlet opening, a stuffing box connected up between the tubes, a spraying head connected with the outer tube, a valve seat formed in the head, a valve for a spraying medium in threaded engagement with the outer tube and coacting with the seat in the spraying head, means to turn the outer tube and thereby move the valve seat thereof, an oil barrel connected with said valve, a threaded boss in the oil barrel, a valve rod in threaded engagement with said boss, a valve seat and port in the oil barrel, a valve extending from the valve rod and coacting with the latter seat, an oil chamber connected with the said inner tube and a stuffing box extending from the oil chamber for said valve rod.

3. In an oil burner the combination of an outer tube, a spraying head connected thereto, a valve seat formed in the head, an inner tube slidably connected with the outer tube, an oil pipe in connection with the inner tube, an oil barrel extending from one end of said pipe and in threaded engagement with the outer tube, a threaded boss in the oil barrel, an oil nozzle extending from the oil barrel coacting with the valve seat formed in the spraying head, a port extending through the oil nozzle, a valve seat formed with said port, an oil chamber connected with the other end of said pipe, a stuffing box connected to said chamber, a valve rod passing through the stuffing box and also through the oil pipe and oil barrel, and in threaded engagement with the

threaded boss in the oil barrel, and a valve extending from the rod coacting with the seat and port in the oil nozzle.

4. In an oil burner the combination of an outer tube, a spraying head connected thereto, a valve seat formed in the head, an inner tube slidably connected with the outer tube, a stuffing box connected up between the two tubes, an oil pipe in the inner tube, an oil barrel connected to one end of said pipe in engagement with the outer tube, a threaded boss in the oil barrel, an oil nozzle extending from the oil barrel adapted to coact with the valve seat in the head, a port through the nozzle and a valve seat formed with the port, a fluted outer surface on the oil nozzle, an oil chamber in communication with the other end of the oil pipe and also connected to the corresponding end of the inner tube, a stuffing box connected to said chamber, a valve rod passing through the stuffing box and also through the oil pipe and oil barrel and in engagement with the threaded boss in the oil barrel, a valve extending from the valve rod coacting with the seat in the oil nozzle, and means to turn the outer tube and thereby axially move the valve seat in the spraying head relatively to the oil nozzle.

5. The combination in a burner of an outer tube, an inner collar extending from the tube and having openings, a support in which said tube is rotatably mounted, a dial plate connected to said support, a pointer extending from said tube, a spraying head connected with said tube, a valve seat formed in the head, a cavity in the head adjacent to said seat, outlets extending from said cavity through the head, threads formed in the collar of the outer tube, a barrel with threads on its outer surface within the tube and in engagement with the threads thereof, a nozzle extending from the barrel and its end face coacting with the valve seat in the head, a valve for fuel located in the nozzle, means to move the valve, a valve seat with a port in the nozzle for said valve, a fuel pipe connected to the barrel, a fuel strainer chamber connected with the fuel pipe, an inner tube with an inlet and slidably connected with the outer tube and a stuffing box connected up between the two tubes.

6. In a burner the combination of an outer tube, a collar extending from the inner surface of said tube and having openings, threads extending from the said collar, a support in which said tube is rotatably mounted, a dial plate connected to said support, a pointer extending from said tube over the dial plate, a spraying head connected to the outer tube, an inner cavity in the spraying head and outlets, extending from the latter through the said head, a valve seat formed in the head adjacent to said cavity, an inner tube slidably connected with the

outer tube and having an inlet opening, a stuffing box connected up between the two tubes, a fuel pipe in the inner tube, a barrel connected to one end of said pipe, threads 5 formed on the outer surface of the barrel in engagement with the threads of the outer tube, a nozzle extending from the barrel and coacting with the valve seat in the head, a port with the valve seat formed in the nozzle, a threaded boss in the barrel, a chamber in communication with the other end of the fuel pipe and also connected to the accompanying end of the inner tube, a stuffing box at one end of the latter chamber, a valve 10 rod passing through the stuffing box and also through the fuel pipe and barrel, and in threaded engagement with the boss in the barrel, and a valve extending from the valve rod coacting with the seat over the port in the nozzle. 15

Signed at the borough of Manhattan in the county of New York and State of New York this 15th day of December A. D. 1908.
